DEVICE FOR DEGASSING AND PURIFYING HYDRAULIC LIQUID OF A HYDRAULIC POWER SYSTEM

Gerhard Caroli, Stuttgart, Germany, assignor to Süddeutsche Kühlerfabrik Julius Fr. Behr, Stuttgart-Feuerbach, Germany

Filed Aug. 14, 1957, Ser. No. 678,128

Claims priority, application Germany Aug. 16, 1956

7 Claims. (Cl. 60—52)

This invention relates to hydraulic systems and more particularly to a device for degassing and purifying hydraulic liquid contained in hydraulic systems such as hydraulic power plants and motors.

The invention is particularly applicable to the degassing and purifying of pressure oil used in hydraulic cooling motors and the like.

It is an object of this invention to provide a device for efficiently degassing and purifying hydraulic liquid of hydraulic systems without influencing the operation of the pump of the system.

A further object of the invention resides in the provision of means for imparting a swirling movement to the hydraulic liquid within a predetermined portion of the hydraulic system while at the same time the liquid is caused to rise within a predetermined confine. The centrifugal force caused by the swirling motion and the slow rising of the liquid causes the gas bubbles in the liquid to rise to the surface and in this way facilitates the degassing of the liquid.

Further objects and details of the invention will be apparent from the following description and the accompanying drawings illustrated—by way of example—an embodiment of the invention. In the drawings:

Fig. 1 is a diagrammatic illustration of the elements of a hydraulic power plant;

Fig. 2 is a vertical cross section through the center of the hydraulic liquid container of the plant; and

Fig. 3 is a horizontal section through the upper chamber of the hydraulic liquid container corresponding to Fig. 2.

Referring now to the drawings, the power plant according to Fig. 1 comprises a pump 1 and a hydraulic motor 3 charged with hydraulic liquid, for example, pressure oil, by the pump 1 through a high pressure line or duct 2. The flow direction is indicated by the arrows. From the motor 3, the hydraulic liquid, which in most instances will be an oil, flows through a return pipe 4 into a cylindrical, hydraulic liquid container 5 and from the latter through a suction pipe 6 back to the pump 1. The cycle is thus completed.

The construction of the container 5 can be seen in detail in Figs. 2 and 3. As is shown in Fig. 2, the container 5 is divided by partition means into an upper chamber 12 and a lower chamber 13. The two chambers 12 and 13 communicate with each other through an overflow pipe 11. The inlet end of this overflow pipe is located in the upper chamber 12 just below the closed front wall of the chamber 12, while the lower or outlet end 11' of the overflow pipe terminates above the inlet end of the suction line 6. The outlet 11' of the overflow pipe 11 is provided with a nozzle 8. The outlet 11' and the inlet of the suction line 6 are rigidly connected with each other by means of strap or bridging members 7. An inlet pipe 14 which is screwedly connected with the return line 4, opens tangentially into the

2

lower half of the upper chamber 12. A magnetic filter 10 is arranged in the upper chamber 12. In the lower chamber 13 of the hydraulic liquid container 5 there is provided an overflow valve 15 and, further, a control valve 15', below the overflow valve, as well as exit or vent means in the form of tube 9.

The hydraulic liquid which is returned from the motor 3 through the return pipe 4 with a certain excess pressure enters the upper chamber 12 of the container 5 tangentially through the inlet pipe 14. The hydraulic liquid is in this manner imparted with a swirling motion and circulates around the permanent magnetic filter 10 and the overflow pipe 11. Both the magnetic filter 10 and the overflow pipe 11 are arranged in parallel relationship relative to the cylindrical axis of the container 5 and in the vicinity thereof. The hydraulic liquid or pressure medium, after it has risen in the upper filter chamber 12, flows through the overflow pipe 11 into the lower chamber 13 which latter chamber, in contrast to the filter chamber 12, is not entirely filled with the pressure medium or hydraulic liquid. The outlet 11' of the overflow pipe 11 terminates below the liquid level of the hydraulic liquid. The pressure medium flows then under excess pressure through the nozzle 8 provided at the outlet end 11' of the pipe 11 into the funnel-shaped enlarged inlet end of the suction line 6. In doing so, the air included or contained in the hydraulic liquid or pressure medium escapes upwardly and collects in the upper portion of the chamber 13 and thus may escape through the vent or discharge tube 9.

As will be readily gathered from the above description, the invention is particularly directed to hydraulic power plants or systems, wherein a hydraulic liquid or oil container is interposed in the line between the hydraulic motor and the pump. Important features of the invention reside therein that the line leading from the motor to the container opens up tangentially into the container, that the hydraulic liquid is discharged below the inlet end of an overflow pipe arranged within the container and conveying the hydraulic liquid, and further, that this overflow pipe is arranged parallel to and in the vicinity of the cylinder axis of the container. By arranging the various elements in this manner, a swirling motion is imparted to the hydraulic liquid within the container, while the hydraulic liquid rises therewith. In this manner, the liquid, upon entering the container is rapidly degassed, whereby the entire line system is liberated from air. Further, during operation, due to the favorable pressure conditions prevailing during this swirling movement, air which may be comprised in the liquid may escape therefrom and rise upwardly whereafter this air is separated from the hydraulic cycle through exit means. In this manner one is assured that the liquid will be entirely degassed while the hydraulic liquid pump will operate quietly without being affected by the degassing procedure.

As has been explained in conjunction with the drawings, in accordance with a preferred embodiment of this invention, a magnetic filter is arranged within the container. Such magnetic filter may advantageously also be used in containers in which no swirling movement of the hydraulic liquid takes place. However, particularly advantageous is the use of such magnetic filter in containers wherein the pressure medium or hydraulic liquid flows through the container in a swirling movement, since due to this swirling movement, the pressure medium is for a relatively longer period under the action of the magnet and thus, the magnetic filter can readily be arranged in the container in such a manner that all the hydraulic liquid which passes through the container will at least once flow past the immediate vicinity of the filter

surface. Consequently, an efficient filter action is obtained.

As has been explained in connection with the drawings, the container, according to a preferred embodiment is divided into two chambers. The return line from the motor opens up tangentially into the upper chamber of the container. From the upper chamber the liquid is conducted into the lower chamber through an overflow pipe. The lower chamber is not entirely filled with the pressure medium. The overflow pipe terminates below the level of the hydraulic liquid in the lower chamber and above the inlet end of the suction line. The outlet of the overflow pipe is nozzle-shaped. In this manner pressure conditions are created in the hydraulic liquid cycle which favorably influence the output of the hydraulic pump and which facilitate and accelerate the degassing of the pressure medium or hydraulic liquid.

It will be apparent to those skilled in the art that many modifications and alterations of the device herein described and illustrated may be made without departure from the essence and spirit of the invention which for this reason shall not be limited but by the scope of the appended claims.

I claim:

1. In a hydraulic system including a fluid motor having an inlet and a discharge, pump means including a pressure line arranged to discharge fluid to said motor inlet and a suction line for said pump connected to said motor discharge, the improvement comprising a degassing device in said suction line, comprising a liquid container including an upper portion having means for maintaining said portion completely filled with liquid and a lower portion having means for maintaining it filled with liquid to a predetermined level, a first portion of said suction line returning from said fluid motor extending into said container adjacent the bottom of said upper portion, a conduit extending between said upper portion and lower portion of said container, said conduit including an upper opening adjacent the top of said upper portion of said container and a lower opening of reduced dimension submerged in the liquid in the lower portion of said container, and a second portion of said suction line including an opening in the liquid of said container lower portion and in alignment with but spaced in an axial direction from the discharge of said conduit lower opening in the direction of discharge flow and extending back to said pump means whereby liquid returning through said suction line to said pump is directed into the upper portion of said container and downwardly through said conduit and into the liquid of said lower container, the turbulence causing gases to be separated therefrom in said lower container and to rise to the surface of the liquid in said container.

2. In a hydraulic system according to claim 1, including a vent at the upper end of the lower portion of said container.

3. In a hydraulic system according to claim 1, wherein said first portion of said suction line is connected tangentially into the upper portion of said container.

4. In a hydraulic system according to claim 1, including bridging means extending between said conduit and said second portion of said suction line.

5. In a hydraulic system according to claim 1, including fluid tap means for discharging water from the lower portion of said container above a predetermined level.

6. In a hydraulic system according to claim 1, including magnetic filter means in the upper portion of said container.

7. A liquid degassing device for positioning in the return line between a hydraulic motor and a hydraulic pump wherein liquid is forced from the motor to the pump, comprising, a liquid container including an upper portion and a lower portion, means for maintaining the upper portion completely filled with liquid, means for maintaining the lower portion filled with liquid to a predetermined level, said suction line including a first portion returning from said motor discharging into said upper portion of said liquid container, a conduit extending from a location adjacent the top of said upper container to a location intermediate the height of said lower portion of said container and terminating in a discharge opening of reduced dimension submerged in the liquid in said lower portion of said container, and a second portion of said suction line including an opening submerged in the liquid of said lower portion in alignment with but spaced in an axial direction away from the discharge opening of said conduit in the direction of discharge flow, said conduit extending back to said pump means, whereby liquid returning from said motor is directed first into the upper portion of said container where it is forced to flow upwardly in said upper portion and then downwardly through said conduit into the liquid of the lower portion of said container and thence into the second portion of said suction line.
